UNITED STATES PATENT OFFICE.

DANIEL C. REYNOLDS, OF PHILADELPHIA, PENNSYLVANIA.

EXTRACTING APPARATUS.

1,263,470.

Specification of Letters Patent. Patented Apr. 23, 1918.

Original application filed June 22, 1916, Serial No. 105,811. Divided and this application filed March 27, 1917, Serial No. 157,828. Renewed February 27, 1918. Serial No. 219,538.

To all whom it may concern:

Be it known that I, DANIEL C. REYNOLDS, a citizen of the United States, residing at Philadelphia, in the county of Philadelphia and State of Pennsylvania, have invented certain new and useful Improvements in Extracting Apparatus, of which the following is a specification.

The object of the invention is to provide an improved apparatus for extracting from barks certain of their ingredients.

Another object is to provide in such an apparatus improved receptacles in which the barks are steeped, and in which the volume of the liquid obtained is reduced by evaporation.

Further objects of the invention consist in providing an apparatus which obtains the greatest possible quantity of extract from a given amount of bark; which consumes the least possible amount of steam; which can be cleaned with the most convenience; which permits the liquid carrying the extract from a given batch of bark to be raised in specific gravity by reboiling with a second batch of bark with the least operation and waste energy; and which in every way increases the efficiency of the process.

The preferred embodiment of the invention comprises elements fully described, and illustrated in the accompanying drawings in which Figure 1 is a perspective view of the whole system; Fig. 2 is a vertical diametrical section of one of the set of extracting tanks; Fig. 3 is a vertical section of the evaporating tank; Fig. 4 is a horizontal section on the line 4—4 of Fig. 3; Fig. 5 is a section on the line 5—5 of Fig. 3; and Fig. 6 is an enlarged detail view of one of the supports used in the tanks for positioning the tubes.

Referring to Fig. 1 of the drawings, the preferred arrangement of the apparatus employed in carrying out the present invention is shown as comprising four extracting tanks A¹, A², A³ and A⁴, provided with drain pipes 1, having regulating valves 2, and leading from the bottoms thereof to a common pipe 3, which drops to a lower level and thence

through branches 4, controlled by valves 5, 50 into storage tanks B¹, B², and B³.

From the lowermost portions of the last-named tanks liquids are led through pipes 8, provided with valves 9, and thence through a common pipe 10 to a centrifugal pump 11, 55 driven by any suitable power (not shown), while from said pump they pass through a pipe 12 upwardly and by branches 13, provided with valves 14, to the upper portions of said first-named tanks. 60

For the purpose of heating the contents of the extracting tanks, and one of the storage tanks, the same are provided with steam coils 18 adjacent to their bottom walls and are of any suitable construction, but preferably of the arrangement shown in Fig. 2, 65 each of said coils communicating at one end through suitable reducing valves 19 with a steam supply line 20, leading from any desired source (not shown). At their 70 opposite ends said coils communicate through individual traps 21 and a common pipe 21' with a vacuum line 22, leading to a vacuum-producing device (also not shown).

From one point of the steam supply line, 75 an extension 23 leads to another coil 24 in the bottom of an evaporating tank 25, said extension being provided with a valve 26, which however is not necessarily of the reducing type, the other end of said coil opening through a trap 27 and a pipe 27' into a condensation well, whence this pure water with its latent heat units is reheated and reinjected into the boiler forming the source of steam supply. Said evaporating tank is 80 adapted to be filled through a pipe 30 into which lead branch pipes 31, provided with individual valves 32, from the bottoms of each of the said storage tanks. 85

The storage tanks are simply cylinders, 90 either with or without covers, but without any special interior construction, except in the case of the one which, as above described, is provided with a steam coil for maintaining the contents of said tank heated until 95 they are drawn off. However, in the extracting tanks the construction is similar to that shown in Fig. 2, and herein lies one of the

principal advantages of the system and process, as compared with those known to be at present in operation.

A tank 35 is provided with a substantially 5 horizontally extending partition 36 at a relatively short distance from its bottom wall, said partition having an aperture 37, while from the sides of the latter is a relatively short section of tube or pipe 38, which extends into, and to a point adjacent to the bottom of, a cup 39, forming with said tube a trap for a purpose hereinafter described. Extending through said partition and upwardly to a point but a short distance below the plane of the upper terminus of the sides of the tank is a series of substantially 15 parallel tubes 41, open at both ends and supported in spaced relation with the sides of the said walls by brackets 42, to which said tubes are secured by straps 43. Spanning the opening 37 in the partition 36 is a suitable strainer 44, which keeps solid particles from entering and clogging said trap.

In the operation of the device as thus far 25 described, one or more of the extracting tanks is substantially filled with very finely divided bark to a point a short distance below the top of the former, while water is poured upon the same until the said bark is 30 covered, the water being preferably supplied in the nature of a spray acting to settle the dust of the bark, while the operation of filling the tank is proceeding.

Steam, preferably at about sixty pounds 35 pressure, is then turned into the coil in the bottom of the tank and the water heated until it boils hard, this action being maintained for approximately twenty-four hours, and during this time the formation of steam 40 adjacent to the coil and below the partition, being unable to pass through the latter by the trap, forces the water in the tubes 41 upwardly in a practically constant stream, whence it sprays over the bark, upon being 45 turned downwardly by apertured caps or deflectors 46, and percolates through the mass. Gradually in this manner the juices of the bark are extracted, and the water containing the same is run off by gravity into 50 any one of the storage tanks.

If the extract thus formed is not sufficiently dense to come up to the required Baumé, the same is run into the storage tank having the heating coil, from whence it is 55 taken and by the centrifugal pump forced upwardly into the original, or another, of the extracting tanks upon a fresh charge of bark. The same process of boiling and percolating is then continued, after which, if 60 the desired specific gravity has been attained, the extract is run off into a storage tank, and then, if desired, into the evaporating tank.

The evaporating tank 25 comprises a cylinder 50, preferably supported by legs 50' 65 and having adjacent to its bottom wall the coil 24 hereinbefore referred to, and near to its upper portion a substantially horizontal partition 51, provided with an aperture 52, partially closed by a strainer 53, and having 70 a tube 54 depending therefrom and into a deep cup 54', to form a trap similar to the one previously described, but larger in proportion for the purpose of accommodating the liquid which before being drawn from 75 the tank is heavy and sluggish like molasses, said cup preferably extending through and below the bottom of the tank, and drainable by a valve 54a.

The upper part of this tank terminates in 80 a large, flaring, funnel-shaped section 55, and a series of parallel tubes 56, extending from below and through said partition, terminate near the lower part of said section, while they are held in spaced relation from 85 the walls thereof by brackets 57, similar to those hereinbefore described. The relatively light liquid extract which enters this evaporating tank, is heated to the boiling point by the steam coil 24, and is forced by the 90 steam upwardly through the said tubes and sprayed into the air, where little by little it loses its moisture and in falling back is led into the tank and thence through the partition by way of the trap described.

Having thus described my invention, what I claim and desire to protect by Letters Patent of the United States is:—

1. In an extracting apparatus, the combination of a tank, a substantially horizontal partition therein having an aperture, a trap partially obstructing said aperture, and operative to permit only a unidirectional flow of liquid through said partition, a series of tubes extending upwardly through said partition, and means in said tank below said partition to heat the contents of the former.

2. In an extracting apparatus, the combination of a tank, a partition therein having an aperture, a trap partially obstructing said aperture and operative to permit only a unidirectional flow of liquid through said partition, a tube extending through said partition to a point near the top of said tank, and a flared extension of the walls of said tank to direct liquid falling thereupon back into said tank.

3. In an extracting apparatus, the combination of a tank, a partition therein having an aperture, a trap partially obstructing the said aperture and operative to permit only a unidirectional flow of liquid through said partition, a tube extending through said partition to a point near the top of said tank, means within said tank and below said partition to heat the contents of the former,

and a flared extension of the walls of said tank operative to direct the liquid falling thereupon back into said tank.

4. An extracting apparatus, comprising a series of extracting tanks, a series of storage tanks, means to lead liquid from any one of said first tanks selectively into any one of said second tanks, means operative to return

liquid from any of the latter tanks to any of the former, and an evaporating tank adapted to receive liquid selectively from any of said storage tanks. 10

In testimony whereof I have affixed my signature.

DANIEL C. REYNOLDS.
